(57) **CLAIM**

We claim the ornamental design for a bracket, as shown and described.

DESCRIPTION

FIG. 1 is a front perspective view of a bracket according to our new design;

FIG. 2 is a top plan view thereof;

FIG. 3 is a bottom plan view thereof;

FIG. 4 is a right-side elevation view thereof;

FIG. 5 is a left-side elevation view thereof;

FIG. 6 is a rear-side elevation view thereof;

FIG. 7 is a front-side elevation view thereof; and,
FIG. 8 is a front perspective view of the bracket fully assembled.

The broken lines depict unclaimed portions of the bracket and form no part of the claimed design. The bracket is shown with a symbolic break in its length. The appearance of any portion of the article between the break lines forms no part of the claimed design.
